DISPENSING MECHANISM FOR VENDING
MACHINES

Alvin W. Holstein, Brentwood, and James T. Schuller, St. Ann's, Mo., assignors, by mesne assignments, to Universal Match Corporation, Ferguson, Mo., a corporation of Delaware

Filed Dec. 26, 1961, Ser. No. 161,836
7 Claims. (Cl. 221—15)

This invention relates to dispensing mechanism for vending machines, and more particularly to a magazine type of article dispensing mechanism of the class in which articles such as candy bars are placed on pivoted shelves located one above another, and dispensed by successively tripping the shelves starting with the lowermost shelf.

This invention specifically is an improvement on the dispensing mechanism shown in Holstein U.S. Patent 2,896,817 issued July 28, 1959. This patent shows a dispensing mechanism of the type above described (which may be referred to as the drop-shelf type of article dispensing mechanism), and in which release of a shelf is effected by pull-out and return of an ejector bar (designated 97 in the patent), with the arrangement such that the shelf is released for full free downward swing upon return of the ejector bar. Each shelf, upon release, rapidly swings downward to drop the candy bar (or other article) thereon. The drop of the shelf may be so rapid that the candy bar (or other article thereon) drops more or less flatwise instead of tilting down with the shelf and dropping more or less endwise. This may be undesirable particularly in the case of longer candy bars or other relatively long articles because of the possibility of such articles becoming jammed in the magazine due to their dropping flatwise instead of endwise.

Accordingly, among the several objects of this invention may be noted the provision of an improved drop-shelf article dispensing mechanism which assures more or less endwise article drop (as distinguished from more or less flatwise article drop) to avoid the possibility of jamming of articles in the mechanism; and the provision of such an improved mechanism which is economical to manufacture and reliable in operation. In general, the improved mechanism involves the provision of means operative upon release of each shelf for delaying the downward swing of the shelf to give the article on the shelf time to tilt down with the shelf, and then to allow the shelf to complete its downward swing so that flatwise drop of the article is avoided. More particularly, the arrangement is such as to arrest the downward swing of each shelf and temporarily hold it in an intermediate position on pull-out of an ejector bar, and then to allow the shelf to complete its drop on return of the ejector bar. Other objects and features will be in part apparent and in part pointed out hereinafter.

The invention accordingly comprises the constructions hereinafter described, the scope of the invention being indicated in the following claims.

In the accompanying drawings, in which one of various possible embodiments of the invention is illustrated,

FIG. 1 is a side elevation of a magazine embodying this invention, a central portion of the magazine being broken away;

FIG. 2 is a front elevation of the magazine, a central portion of the magazine again being broken away;

FIG. 3 is a top plan view of the magazine, on a larger scale than FIGS. 1 and 2, a portion being broken away;

FIG. 4 is a vertical section taken on line 4—4 of FIG. 3 and showing the upper three shelves of the mechanism, the uppermost shelf and the second shelf down from the top being shown in their horizontal article-carrying position, and the third shelf down from the top

2

being shown in its released position hanging downward;

FIG. 5 is a horizontal section taken on line 5—5 of FIG. 4, omitting a trip on the next shelf above;

FIG. 6 is a fragment of FIG. 5 illustrating a moved position of parts;

FIG. 7 is a vertical section taken on line 7—7 of FIG. 5;

FIG. 8 is an enlarged horizontal section taken on line 8—8 of FIG. 1;

FIG. 9 is a vertical section taken on line 9—9 of FIG. 3;

FIG. 10 is a view similar to FIG. 4, showing the third shelf down from the top in its arrested intermediate inclined position (as distinguished from its completely released FIG. 4 position); and

FIG. 11 is a fragmentary rear elevation.

Corresponding reference characters indicate corresponding parts throughout the several views of the drawings.

Referring to the drawings, a magazine of the type shown in U.S. Patent 2,896,817 and improved in accordance with this invention is designated in its entirety by the reference character M. The magazine is shown to comprise a frame or support generally designated 1 supporting a plurality of pivoted article-carrying shelves. The frame or support 1 comprises a vertical sheet metal channel member 3 and a vertical side plate 5. The side flanges of the channel member are designated 7 and 9. The web of the channel member, which constitutes the back of the magazine M, is designated 11. This has a plurality of rectangular openings 12. The vertical side plate 5 is secured to the outside of the flange 9 of the channel 3. This plate 5 has an outwardly offset portion 13 forward of the flange 9. The channel 3 is longer than the plate 5 and extends down below the lower edge of the plate.

The article-carrying shelves are located one above the other. For simplifying the disclosure, only six shelves are shown in FIGS. 1 and 2. It will be understood, however, that a commercial embodiment of the magazine will have more than six shelves. For example, a typical commercial magazine will have twenty shelves. The shelves, which are all identical, are generally designated by the reference character 15, the bottom shelf being specially designated 15b and the top shelf 15t. Each is pivotally mounted at its rearward end between the flanges 7 and 9 of the channel 3 for swinging movement on a horizontal axis, by means of a special hinge member 17 to be described.

Each shelf, which is preferably a one-piece plastic molding, has an integral downwardly directed flange 19 at its rearward end. Integrally molded reinforcing ribs for the shelf are indicated at 21 and 23. At each of the lower corners of the flange 19, and on the back of the flange, hinge eyes 25 and 27 are provided for the hinge member 17. These may be molded as integral parts of the shelf. Hinge member 17 comprises a piece of spring wire, bent so as to have a loop portion 29 of inverted U-shape, and horizontal hinge pin portions 31 and 33 which

extend laterally outward from the ends of the sides of the loop portion. Pin 31 is slidably received in the eye 25, and pin 33 is slidably received in the eye 27. As to each of the shelves, pin 31 is slidably and rotatably received in a hole 35 in the flange 7 of channel 3, and pin 33 is slidably and rotatably received in a hole 37 in the flange 9.

Also, for each of the shelves, the side plate 5 has a hole 39 in line with the hole 37 for receiving the pin 33.

The loop 29 extends upward on the back of the shelf flange 19 and is confined against swinging outward away from the flange 19 by having one of its sides received in a notch 41 in a lug 43 which projects rearward from the

back of the flange 19. This lug may be molded as an integral part of the shelf. The lower end of the stated side of the loop is engageable with a stud 45 which projects rearward from the back of flange 19. This stud may be molded as an integral part of the shelf. The flange 19 has an opening 47 for access to the other side of the loop from the front of flange 19. The arrangement is such that a tool, such as a screw driver, may be inserted in the opening 47 from the front for pushing the accessible side of the loop toward its other side to retract the pin 31 from the hole 35 for removal of the shelf from between the channel flanges 7 and 9.

On the back of the flange 19 of the each shelf, below the lug 43, is a lug 49. Lug 49, like lug 43, may be molded as an integral part of the shelf. These lugs 43 and 49 carry a metal bushing 51 (see FIG. 9, particularly) for the pivotal mounting on the back of the flange 19 of a catch 53 and a trip 55 for the catch. The bushing extends parallel to the flange 19 in a plane perpendicular to the flange 19, being received in suitable openings in the lugs and having its ends projecting from the lugs. The catch 53 comprises a sheet metal stamping having an ear 57 overlying the upper lug 43. This ear is provided with an opening receiving the upper end of the bushing 51. The catch is also formed to have a bottom arm 59 underlying the lower lug 49 and provided with an opening receiving the lower end of the bushing. Above the bar 57, the catch has an upper arm 61 in the form of a hook. The trip 55 comprises a length of metal rod bent to have a portion 63 which is rotatably received in the bushing 51, a laterally projecting upper arm 65, a portion 67 extending downward from the outer end of arm 65, and an angled feeler arm 69 at the lower end of portion 67 below the level of the bottom of the flange 19.

The catch 53 is biased in clockwise direction as viewed from above (and as viewed in FIG. 3) by a spring 71 to the latching position shown best in FIGS. 3 and 5 wherein the hook 61 extends rearward generally perpendicular to the flange 19. This position of the catch is determined by engagement of a portion 73 of the catch with the back of the flange 19. The portion 67 of the trip 55 is engageable with the bottom arm 59 of the catch. The trip is biased in clockwise direction as viewed from above (and as viewed in FIG. 3) by a spring 75 (see FIGS. 4 and 7). The bias of spring 75 is weaker than that of spring 71.

The hook 61 of the catch 53 of each shelf is engageable with a lug 77 which extends inward from the flange 9 of the channel 3. There is a separate lug 77 for each catch, the lugs being formed by striking inward portions of the flange 9. With a catch in the latching position as shown in FIGS. 3 and 5 and with the respective hook 61 engaging the respective lug 77, the respective shelf is held latched in the horizontal article-carrying position such as is shown in FIG. 1 for all the shelves and as shown in FIG. 4 for the two top shelves.

For operating the trips 55 to operate the catches 53 to release the shelves, there is provided a rotary member 79 which extends vertically within the channel 3 in back of the shelves. This member 79 consists of a sheet metal angle bar having pivot pins 81 and 83 welded to its upper and lower ends. The pin 81 is journaled in a lug 85 struck in from the back of the channel 3 near the upper end of the channel, and the pin 83 is journaled in a lug 87 struck in from the back of the channel near the lower end of the channel. The bar 79 has a plurality of fingers 89 for engagement with the lateral arms 65 of the trips 55.

On the back of the flange 19 of each shelf is a cam 91. This may be molded as an integral part of the shelf. As to each shelf (except the uppermost shelf), when it is held by its catch 53 in its raised article-carrying position, its cam 91 engages the feeler 69 of the trip 55 of the next shelf above to hold this trip in a retracted position such as is shown for the shelf 15₁ in FIG. 3.

As to each shelf (except the lowermost shelf), its trip 55 is released for movement under the bias of spring 75 from the retracted position to an operative position such as is shown in FIG. 5 when the next shelf below is released from its raised article-carrying position and swings downward. When a trip 55 is in its retracted position, its lateral arm 65 lies clear of the path of movement of the respective finger 89 on the trip-operating bar 79. When a trip 55 is in its operative position (the shelf which carries the trip being in the raised position), the lateral arm 65 of the trip is positioned for engagement by the respective finger 89 on the bar 79 (see FIG. 5).

The construction thus far described is the same as disclosed in the aforementioned U.S. Patent 2,896,817. In accordance with this invention, each trip 55 has welded to the angled feeler arm 69 thereof a length of metal rod 69a. This extra rod 69a extends lengthwise of arm 69 on the back side thereof and has a rearwardly projecting curved finger 69b at its end toward portion 67 of trip 55. Also, fingers 89 on the trip-operating bar 79 are modified as regards fingers 89 shown in U.S. Patent 2,896,817, each finger 89 having a relatively wide base portion 89a (see particularly FIG. 11) the bottom edge 89b of which constitutes a shoulder adapted for engagement by finger 69b on the respective trip in a manner that will be made clear.

The trip-operating bar 79 normally occupies the retracted position in which it is shown in solid lines in FIG. 3. In this position, the leg of bar 79 on which fingers 89 are formed projects from the vertical axis of the bar (determined by pivot pins 81 and 83) laterally toward the right from the axis (as viewed from the front of the magazine M), and fingers 89 extend laterally adjacent the back 11 of the magazine M. Bar 79 is biased by a spring 92 to swing toward the stated retracted position, the latter being determined by engagement of the ends of certain fingers 89 with portions of the back 11 of magazine M between the rectangular openings 12 in back 11. In this respect, the construction is also different from the construction shown in U.S. Patent 2,896,817 where fingers 89 in their retracted position extend toward the front.

Means is provided for rotating the trip-operating bar 79 in clockwise direction away from its stated retracted position as viewed from above (and as viewed in FIGS. 3 and 5) to a position such as shown in FIG. 6, and then back to retracted position for operating a trip 55. As shown in FIGS. 1, 2 and 8, this means comprises a lever 93 pivoted at 95 on the outside of flange 9 of channel 3 adjacent the lower end of the channel. An ejector bar 97 has its rearward end pivotally connected to the upper end of the lever 93, as indicated at 99, and extends upward and forward on the outside of portion 13 of plate 5. A guide strap such as indicated at 101 may be struck out from plate 5 for guiding bar 97. This is not essential. A lever 103 is pivoted at 105 for swinging on a vertical axis on a bracket 107 secured to the back 11 of magazine M. Lever 103 extends through a slot 109 in flange 9 of channel 3 into a hole 111 in lever 93. A lever 113 is pivoted at 115 on bracket 107 for swinging movement on a vertical axis in a plane above lever 103. Lever 113 has a cam slot 119. Lever 103 carries a roller 121 which extends into the slot 119. A triangular plate 123 constituting a crank is welded to the lower end of bar 79. A crank pin 125 extends down from plate 123 into the slot 119.

The ejector bar 97 and the lever 93 normally occupy the rearward retracted position in which they are shown in FIG. 1. With bar 97 and lever 93 in retracted position, the trip-operating bar 79 is in its retracted position illustrated in FIGS. 3, 5 and 8. On pulling out the ejector bar 97, lever 93 is swung forward (clockwise as viewed in FIG. 1). This swings lever 103 clockwise as viewed in FIG. 8. The roller 121 on lever 103 swings lever 113 counterclockwise as viewed in FIG. 8, and lever 113, acting through crank pin 125 extending into slot 119 in

lever 113, rotates the trip-operating bar 79 in clockwise direction as viewed in FIGS. 3, 5 and 8 away from its retracted position shown in FIGS. 3, 5 and 8 to the position shown in FIG. 6. On return of the ejector bar to its rearward retracted position (as by pushing it back), the trip-operating bar 79 is rotated in counterclockwise direction back to its retracted position.

Means is provided for locking the entire mechanism out of operation when the top shelf 15t has been released. As shown best in FIGS. 1 and 4, this means comprises a latch 131 mounted for vertical sliding movement on the outside of flange 9 of channel 3 adjacent its lower end. The mounting of this latch is effected by means of screws 133 extending through vertical slots 135 in the latch and threaded in flange 9. Pivoted at 137 on the inside of the flange 9 of channel 3 adjacent its upper end is a bell crank lever 139. One arm 141 of this lever extends downward for engagement by the back of the flange 19 of the top shelf 15t when this shelf is in its raised article-carrying position (see FIG. 4). The other arm 143 of this lever extends rearward and has a finger 145 which projects laterally outward through an opening 147 in flange 9 and plate 5. A wire 151 connects finger 145 and the latch 131. When the shelf 15t is in raised position, the bell crank lever 139 is held in the position shown in FIG. 4 and acts through the wire 151 to hold the latch in the raised position shown in FIG. 1. When the shelf 15t is released, the bell crank lever is released and the latch slides down under its own weight into a position wherein it blocks the lever 93 from swinging forward, thereby locking the mechanism out of operation.

It will be understood a plurality of magazines, such as above described, are mounted side-by-side in a vending machine cabinet (not shown) and that push-pull rods are provided which extend out of the front of the cabinet for actuating the ejector bars 97 of the magazines.

In a typical vending machine in which the magazines are used, access to the forward end of the lowermost shelf 15b for raising it is blocked when this shelf is in its lowered position. Accordingly, means is provided for swinging the lowermost shelf 15b back into its raised horizontal position which is readily accessible. As shown best in FIGS. 1 and 2, this means comprises a lever 153 pivoted at 155 on the inside of the flange 9 of channel 3 toward the lower end of the channel. A lever 157 is pivoted at 159 on the inside of flange 9 toward the upper end of the channel. A wire 161 connects the levers 153 and 155. Lever 153 has a roller 163 for engaging the bottom shelf 15b, the arrangement being such that by swinging lever 157 down, lever 153 is raised to raise the shelf 15b.

Operation is as follows:

Assuming that all the shelves are latched in their raised horizontal article-carrying position as illustrated in FIGS. 1 and 2 by engagement of the hooks 61 of the catches 53 with the lugs 77, the trips 55 of all the shelves, except the bottom shelf 15b, will occupy their retracted position such as is shown for the uppermost shelf 15t in FIG. 3. The trip for the bottom shelf will occupy its operative position such as is shown for the trip in FIG. 5. It will be understood that each shelf will carry an article such as a bar of candy to be dispensed. On the first pull-out and return of the ejector bar 97, the trip-operating bar 79 is rotated away from the retracted position in which it appears in FIGS. 3, 5 and 8 to an advanced position such as shown in FIG. 6. Upon rotation of the trip-operating bar 79 from its retracted position to the stated advanced position, the lowermost finger 89 on the bar engages the lateral arm 65 of the trip 55 of the bottom shelf, and rotates this trip 55 in counterclockwise direction as viewed from above. Portion 67 of the trip being in engagement with the bottom arm 59 of the catch 53 of the bottom shelf, the hook 61 of the catch is rotated out of engagement with the respective lug 77 thereby to free the shelf 15b

so that it may swing downward under its own weight and the weight of the item thereon. None of the shelves above the bottom shelf are released, however, because their trips are in retracted position. With trip-operating bar 79 in its advanced FIG. 6 position, the downward swing of the bottom shelf 15b is arrested by engagement of finger 69b on trip 55 of the bottom shelf with the bottom shoulder 89b of the lowermost finger 89 on the trip-operating bar 79 temporarily to hold the bottom shelf in an intermediate inclined position corresponding to that illustrated for the third shelf down from the top in FIG. 10. This gives time for the item on the bottom shelf to tilt down with the shelf. Then, when the trip-operating bar 79 returns to retracted position, finger 69b is released from under the lowermost finger 89 on the bar to allow the bottom shelf to complete its downward swing. The item on the bottom shelf then drops off, flatwise drop being avoided by reason of the tilt of the item.

When the bottom shelf 15b is released and swings downward, the cam 91 on the back of the flange 19 of the bottom shelf moves away from the feeler 69 of the trip 55 of the second shelf. The trip 55 of the second shelf thereupon moves under the bias of spring 75 from its retracted position to its operative position. Then the next time the trip-operating bar 79 is rotated away from and back to its retracted position by pulling out and pushing in the ejector bar 97, the second shelf is released to swing downward and dispense the article thereon. The release of the second shelf is effected in the same manner as that above described for the bottom shelf, except that it is the second finger upon the trip-operating bar 79 that effects the release. None of the shelves above the second shelf are released, however because their trips are in retracted position. When the second shelf is released, the trip 55 of the third shelf is released, and the next time the bar 79 is operated, the third shelf is released. In each instance, the shelf is arrested in the intermediate inclined position such as shown for the third shelf down from the top in FIG. 10 by engagement of the finger 69b on the trip 55 of the shelf with the respective finger 89 on the trip-operating bar 79, then re-released to allow it to complete its drop upon return of bar 79 to retracted position.

Thus, the shelves are successively released, with delayed action as to each shelf to avoid flatwise drop of the item thereon, starting with the lowermost shelf on up to the top shelf. When the top shelf is released and the magazine is empty, the latch 139 slides down and locks the bar 97 against operation. To restore the shelves to raised position, the lowermost shelf is raised by means of lever 157, then the remaining shelves are raised by lifting their forward ends.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrated and not in a limiting sense.

What is claimed is:

1. Article dispensing mechanism comprising a plurality of shelves located one above another, each shelf being pivoted for swinging movement on a horizontal axis and adapted to swing downward from a generally horizontal article-carrying position to a generally vertical discharge position for discharge of an article thereon, means for holding the shelves in said article-carrying position, and means for successively releasing the shelves, starting with the lowermost shelf, said releasing means including means for delaying downward swing of each shelf to avoid flatwise drop of the article thereon, said delaying means comprising means operable upon the release of each shelf for

arresting the downward swing of the shelf and temporarily holding it in an intermediate inclined position prior to discharge of the article carried by the shelf.

2. Article dispensing mechanism comprising a plurality of shelves located one above another, each shelf being pivoted for swinging movement on a horizontal axis at one end thereof and adapted to swing downward from a generally horizontal article-carrying position to a generally vertical discharge position for discharge of an article thereon, means for latching the shelves in said article-carrying position including a series of catches, one for each shelf, means for successively releasing the catches, starting with the catch for the lowermost shelf, comprising a series of trips, one for each catch, and a release bar movable away from and back to a retracted position for successively operating the trips, starting with the trip for the catch for the lowermost shelf, each trip being movable between a retracted position clear of the bar and an operative position engageable by the bar and biased toward operative position, each shelf when in article-carrying position being engageable with the trip for the catch for the next shelf above to hold this trip in retracted position clear of the bar, said bar on successive operations thereof being engageable with the trip for the catch of the lowermost shelf and then engageable with the trips for the catches of each successive shelf as each successive trip moves into operative position on downward swing of the next shelf below, and said releasing means including means for delaying downward swing of each shelf to avoid flatwise drop of the article thereon, said delaying means comprising means operable upon release of each shelf for arresting the downward swing of the shelf and temporarily holding it in an intermediate inclined position.

3. Article dispensing mechanism comprising a support, a plurality of shelves carried by the support located one above another, each shelf being pivoted on the support for swinging movement on a horizontal axis at one end of the shelf and adapted to swing downward from a generally horizontal article-carrying position to a generally vertical discharge position for discharge of an article thereon, means for latching the shelves in said article-carrying position comprising a series of catches, one for each shelf, each catch being mounted on the respective shelf, and means on the support engageable by the catches for holding the shelves each in its said article-carrying position, means for successively releasing the catches, starting with the catch for the lowermost shelf, comprising a series of trips, one for each catch, and a release bar mounted on said support for swinging movement on a vertical axis at said end of the shelves away from and back to a retracted position for successively operating the trips, starting with the trip for the catch for the lowermost shelf, each trip being mounted on the respective shelf for movement thereon between a retracted position clear of the bar and an operative position engageable by the bar and biased toward operative position, each shelf when in article-carrying position being engageable with the trip on the next shelf above to hold this trip in retracted position clear of the bar, said bar on successive actuations thereof being engageable with the trip on the lowermost shelf and then engageable with the trips on successive shelves as each successive trip moves into operative position on downward swing of the next shelf below, and said releasing means including means for delaying the downward swing of each shelf to avoid flatwise drop of the article thereon, said delaying means comprising means operable upon release of each shelf for arresting the downward swing of the shelf and temporarily holding it in an intermediate inclined position.

4. Article dispensing mechanism comprising a plurality of shelves located one above another, each shelf being pivoted for swinging movement on a horizontal axis and adapted to swing downward from a generally horizontal article-carrying position for discharge of an article thereon, means for holding the shelves in said article-carrying position.

cle-carrying position, and means for successively releasing the shelves, starting with the lowermost shelf, said releasing means including means for delaying downward swing of each shelf to avoid flatwise drop of the articles thereon, said delaying means comprising means operable upon release of each shelf for arresting the downward swing of the shelf and temporarily holding it in an intermediate inclined position, said releasing means including a manually operable member movable away from and back to a retracted position, and said arresting means being movable away from a retracted position into position for arresting downward swing of the shelf in response to movement of said member away from retracted position, and movable back to retracted position on return of said member to retracted position for release of the shelf to allow it to complete its downward swing.

5. Article dispensing mechanism comprising a plurality of shelves located one above another, each shelf being pivoted for swinging movement on a horizontal axis at one end thereof and adapted to swing downward from a generally horizontal article-carrying position for discharge of an article thereon, means for latching the shelves in said article-carrying position including a series of catches, one for each shelf, means for successively releasing the catches, starting with the catch for the lowermost shelf, comprising a series of trips, one for each catch, and a release bar movable away from and back to a retracted position for successively operating the trips, starting with the trip for the catch for the lowermost shelf, each trip being movable between a retracted position clear of the bar and an operative position engageable by the bar and biased toward operative position, each shelf when in article-carrying position being engageable with the trip for the catch for the next shelf above to hold this trip in retracted position clear of the bar, said bar on successive operations thereof being engageable with the trip for the catch of the lowermost shelf and then engageable with the trips for the catches of each successive shelf as each successive trip moves into operative position on downward swing of the next shelf below, said releasing means including means for delaying downward swing of each shelf to avoid flatwise drop of the article thereon, said delaying means comprising means operable upon release of each shelf for arresting the downward swing of the shelf and temporarily holding it in an intermediate inclined position, and said arresting means comprising means on each shelf engageable with said bar upon movement of said bar away from retracted position and resultant release of the shelf to arrest the shelf in said intermediate position, the shelf being released to allow it to complete its downward swing upon return of said bar to retracted position.

6. Article dispensing mechanism comprising a support, a plurality of shelves carried by the support located one above another, each shelf being pivoted on the support for swinging movement on a horizontal axis at one end of the shelf and adapted to swing downward from a generally horizontal article-carrying position for discharge of an article thereon, means for latching the shelves in said article-carrying position comprising a series of catches, one for each shelf, each catch being mounted on the respective shelf, and means on the support engageable by the catches for holding the shelves each in its said article-carrying position, means for successively releasing the catches, starting with the catch for the lowermost shelf, comprising a series of trips, one for each catch, and a release bar mounted on said support for swinging movement on a vertical axis at said end of the shelves away from and back to a retracted position for successively operating the trips, starting with the trip for the catch for the lowermost shelf, each trip being mounted on the respective shelf for movement thereon between a retracted position clear of the bar and an operative position engageable by the bar and biased toward operative position, each shelf when in article-carrying position being engageable

with the trip on the next shelf above to hold this trip in retracted position clear of the bar, said bar on successive actuations thereof being engageable with the trip on the lowermost shelf and then engageable with the trips on successive shelves as each successive trip moves into operative position on downward swing of the next shelf below, said releasing means including means for delaying the downward swing of each shelf to avoid flatwise drop of the article thereon, said delaying means comprising means operable upon release of each shelf for arresting the downward swing of the shelf and temporarily holding it in an intermediate inclined position, and said arresting means comprising means on each shelf engageable with said bar upon movement of said bar away from retracted position and resultant release of the shelf to arrest the shelf in said intermediate position, the shelf being released to allow it to complete its downward swing upon return of said bar to retracted position.

7. Article dispensing means as set forth in claim 6

wherein said bar has a series of fingers, one for each trip, each engageable with the respective trip when the latter is in its operative position for releasing the respective catch, and wherein said means on each shelf engageable with said bar comprises a finger on the trip on the shelf, the finger on each trip on each shelf being engageable with the respective finger on the bar when the latter is moved away from retracted position and the shelf is released to arrest the shelf in said intermediate position, the finger on the trip being released to allow the shelf to complete its downward swing on return of the bar to retracted position.
